STRAP STRETCHING DEVICE

Fred H. Hofing, Sharpsville, Pa., assignor to Westinghouse Electric & Manufacturing Company, East Pittsburgh, Pa., a corporation of Pennsylvania

Application November 24, 1943, Serial No. 511,549

8 Claims. (Cl. 254—79)

My invention relates to devices for stretching or tightening straps or bands of metal about a substantially solid mass and for maintaining a predetermined tension on the strap or band until it is fastened. The invention is adapted for applying steel bands about core structures of transformers where it is desirable to apply the band under a predetermined tension to maintain a constant predetermined pressure on the core parts enclosed by the band.

Devices for stretching or tightening a strap or band around a box or package are known, but generally these articles about which the band is placed are compressible, and there is no particular reason for maintaining a predetermined tension of the strap thereon. When the article enclosed by the strap is compressible, no rapid increase in the tension of the strap takes place upon operation of the stretching device. However, when a solid article such as the iron core of a transformer is to be enclosed within a metal strap under a predetermined tension, it becomes necessary to provide for controlling this tension, since a relatively slight stretching of the strap beyond the desired value will greatly increase the stresses on it and may cause it to break, and failure to bring the strap to the desired tension will cause it to fail in its purpose of maintaining a predetermined desired force on the parts of the core.

Transformer cores have been made in which the core parts are formed of loops of magnetic material wound layer upon layer and bounded together. The loops are then cut to form two U-shaped core portions which are assembled about the coils of the transformer and held in place by metal straps placed about the core loops. The strap is drawn to a predetermined tension and fastened in place to maintain a desired predetermined pressure upon the butt joints between the two U-shaped portions of the core loop. With the ordinary tool employed for stretching the strap about the usual type of article, it is difficult to apply the desired pressure because a very slight increase in the stretch in the strap about the solid mass of iron greatly increases its tension. If this tension is much too great, the strap will break. If it is not great enough, the strap will not maintain the desired pressure on the butt joints. In a copending application of Nick Mars for Strap stretching devices, filed June 11, 1943, Serial No. 490,442, and assigned to the same assignee as the present application, a strap stretching device is described provided with means for locking the operating mechanism

when a predetermined tension on the strap has been effected. In this prior device in which the force is applied by hand to a lever carried upon another lever which communicates the force to the operating mechanism, means is provided for locking the second named lever when the force conveyed between the two levers reaches a predetermined value. It has been found, however, that in certain cases, such, for example, as when the strap is applied to very small core loops, this tripping of the locking mechanism is at a point on the "travel" of the operating levers where the locking pin cannot mesh with the locking rack. If the locking mechanism trips in a position so that the locking pin is opposite a tooth of the locking rack, it is necessary to stretch the band an additional amount equivalent to the width of one tooth on the locking rack before the locking device will engage properly.

In accordance with my invention, the lever that is engaged by the hand and directly operated manually, and from which force is communicated to the second named lever is the one that is locked, so that when the force between the two levers has increased to that value causing the locking mechanism to operate, the force exerted on the operating mechanism will be communicated between the two levers through compression springs which absorb or "weigh" the force communicated.

It is an object of the invention to provide a strap stretching device that will bring the strap to the desired tension about a solid article and will not increase the tension above the desired amount.

It is a more particular object of the invention to provide a strap stretching tool of the above indicated character employing a manually operated member from which force is applied to the strap through biasing means that measure the tension on the strap and in providing locking means for the manually operated member that is operable upon a predetermined force being conveyed through the biasing means for locking the manually operated member against operation in either direction and in maintaining pressure on the strap through the biasing means after operation of the locking means.

It is a further object of the invention to provide a strap stretching device of the above indicated character in which the tension on the strap will not be increased above the desired value because of failure of the locking members to engage in the positions occupied by them at the instant of tripping.

Other objects and advantages of the invention will be apparent from the following description of a preferred embodiment of the invention, reference being had to the accompanying drawings, in which:

Figure 1 is an elevational view of a core loop with the strap stretching device applied for stretching a steel strap about the loop.

Fig. 2 is a side elevational view of the strap stretching device with a part of the casing removed to illustrate the operating mechanism.

Fig. 3 is a sectional view of a part of the device taken on the line III—III of Fig. 2.

Fig. 4 is a side elevational view of the strap stretching device with a portion of the operating mechanism shown in section.

Fig. 5 is a sectional view taken along the line V—V of Fig. 4, with the two operating levers in close position to each other.

Fig. 6 is an end view of the two operating levers in close position to each other, and

Figs. 7 and 8 are diagrams illustrating the difference between the operating principle of a prior art device and the device of this invention.

Referring to the drawings and particularly to Fig. 1 thereof, the tool 1 is shown in position for applying a strap about a core loop 2 comprising two U-shaped portions 3 and 4 having butt joints between them along the adjoining surfaces 5. The tool is used to apply the metal strap 6 about the core loop under a predetermined tension so as to maintain a continuous pressure between the two U-shaped portions 3 and 4 at the butt joint surfaces 5. As shown, one end 7 of the strap 6 extends over the corner of the core and along the surface of the loop passing under a fastening clip or sleeve 8 and is bent at 9 to return through the clip or sleeve 8 which surrounds the strap, the strap continuing over the end portion 7 and passing about the core loop and again passing through the clip 8, the end 11 being positioned so as to be gripped by the tool for tightening it about the core loop.

After the strap has been pulled tight about the core loop by the tool 1, the clip 8, which is in the form of a sleeve or band of metal about the two ends of the strap 6, is crimped or deformed sufficiently so that the edges of the clip and of the two ends of the strap passing through the clip are bent to prevent the strap from loosening. This is done in a well known manner and is not a part of the invention, and, therefore, is not described in greater detail.

The tool comprises a frame member 12 formed integrally with a handle 13, the frame member including a casing section 14 normally secured to the portion 12 by screws 15 to form a unitary part of the casing. A lower flat surface 16 of the complementary frame portions 12 and 14 extends horizontally in a plane substantially parallel with the handle 13. The lower portion of the casing section 14 is provided with a foot or flange 17 projecting laterally therefrom and which extends horizontally above the surface of the article about which the steel strap is to be stretched. The gripping member 18 mounted on the pivot pin 19 in the frame structure cooperates with the upper surface of the flange 17 for gripping the end 11 of the metal strap passing between the members 17 and 18. The member 18 is provided with a serrated gripping lower surface 23 for tightly gripping the strap. The gripping member 18 is normally moved into engagement with the end 11 of the strap by means of a coil spring 24 which engages a recess 25 formed in the gripping mem-

ber and bears against a flange 26 formed in the casing portion 14. It will be noted that the position of the gripping member 18 is such that as the end 11 of the strap 6 is pulled toward the right as viewed in Fig. 1, it tends to tighten the grip of the member 18 on the strap and to press it more tightly against the foot or flange 17.

The casing members 12 and 14 are provided with a horizontal guideway which is adapted to receive and guide the movement of a rack bar 28 formed with an enlarged head 29 at one end thereof and provided with teeth 31 on the upper side thereof. The head 29 may be provided with gripping members similar to the members 17 and 18 but is shown as provided with a foot or flange member 32 which is positioned below the end 11 of the metal strap and above the other end of the strap to the right of the clip 8 as shown in Fig. 1. An upper member 33 is positioned above the end 11 of the strap and mounted on a pin 34 attached to the head 29. The members 32 and 33 provide the jaws of the "duckbill" for engaging the end of the clip 8 for forcing the clip in a direction away from the gripping members 17 and 18 mounted on the frame.

The gripping members comprising the parts 17 and 18 and the gripping member comprising the parts 32 and 33 form two relatively movable gripping members which are operated away from each other for the purpose of stretching the strap 6 about the core loop. The mechanism for effecting this operation comprises a pinion having teeth for engaging the teeth 31 on the rack bar. This pinion is not shown in the drawings but is integrally attached to the shaft 37 shown in Fig. 2 extending between the two walls of the casing sections 12 and 14 and upon which the ratchet wheel 38 is also fixedly mounted, so that the pinion (not shown) and the ratchet wheel 38 rotate together. The ratchet wheel 38 is provided with teeth 39 adapted to be engaged by a pawl 42 which is located within the chamber between the casing members 12 and 14 and pivotally connected by a pin 45 to an extension of an operating lever 46 which is pivotally mounted on a pin 47 carried by the casing members. The upward movement of the lever 46 from the position illustrated in Figs. 1, 2 and 3 causes the pawl 42 to move downwardly in engagement with the teeth 39 of the ratchet wheel to move the ratchet wheel 38 and the pinion engaging the teeth 31 in a clockwise direction to move the head 29 of the rack bar toward the left as shown in the drawings.

The pawl 42 is normally held in engagement with the teeth 39 of the ratchet wheel by a spring 48 mounted about a pin 49, the lower end of which is positioned in a socket 51 formed in the upper side of a detent 52 which is pivotally mounted on a pin 53 mounted in the casing structure. The detent 52 is provided with a tooth 54 adapted to engage the teeth 39 of the ratchet wheel to prevent reverse rotation thereof. The upper end of the pin 49 extends through a bore in a projecting head 56 forming a part of the pawl 42. The lower end of the spring 48 engages a collar 57 on the pin 49 and the upper end of the spring 48 engages the projecting head 56. When the pawl is operated to rotate the ratchet wheel 38 the detent 52 rides over the teeth 39 of the ratchet wheel and engages a tooth in a new position to hold the ratchet wheel against reversed rotation during a reverse movement of the pawl 42.

To permit the release of the ratchet wheel and to allow a reverse movement of the ratchet wheel 38 and pinion and a return movement of the head

29 toward the frame, after these parts have been actuated to effect the desired stretching of the steel strap 6, the detent 52 is moved upwardly about its pivot 53 and the pawl 42 is simultaneously moved out of engagement with the ratchet teeth 39. This operation is effected by a releasing member 60 mounted on a shaft 61 and provided with a projection 62 adapted for engaging the under side of the detent 52 and provided also with an upwardly extending part 63 which serves as a cam to effect movement of the pawl 42 away from engagement with the teeth 39 of the ratchet wheel. Any suitable means may be provided for rotating the shaft 61 in a clockwise direction to effect the release of the pawl 42 and the detent 52 to engage the teeth of the ratchet wheel 38.

In order to provide for limiting the pressure or tension to be applied to the steel strap 6, a second lever 70 is provided having one end mounted on the pivot 47 upon which the lever 46 is mounted. The lever 70 is provided with side flanges 71 extending upwardly on the opposite sides of the lever 46 when the two are brought into close relation. The body portion 72 of the lever is provided with bores or sockets 76 opposite similar bores 77 in the underside of the lever 46 and between which coil springs 78 are positioned with their opposite ends in the bores 76 and 77.

A locking member 81 is provided and is shown as having a cylindrical shaft portion 82 extending through a bore 83 in the body of the lever 70 for slidable endwise movement therein. The locking member 81 is provided with a tooth 84 that is adapted to engage between the teeth 75 on the rack member 74 and is provided also with an outer member 85 extending along the side of the rack 74 for providing ready manual operation of the locking member to release the tooth 84 from engagement with the rack teeth 75. A spring 86 is provided about the outer end portion of the shaft 82 in an enlarged portion of the bore 83, one end of the spring engaging an abutment 87 and the other end engaging the flange 88 on the shaft 82 adjacent the tooth 84 for biasing the locking member 81 outwardly to case engagement of the teeth 84 and 75. As best shown in Fig. 5, a spring clip 91 is provided within a bore in the body portion 72 shown attached thereto at 92 and having the end 93 extending across the lower side of the shaft 82 to engage serrations therein at 94 to hold the shaft 82 in the position illustrated in Fig. 4 with the tooth 84 out of engagement with the teeth 75. A pin 95 is provided within a bore 96 in the body portion 72 of the lever 70, the lower end of which extends through a slot 97 in the shaft 82. The upper end of the pin 95 extends upwardly above the upper surface of the body portion 72 of the lever 70 and is positioned to engage the lower end of a set screw 98, shown as screw threadedly fixed in position in the upper lever 46 and held in a desired position by a nut 99. By varying the extent of the projection of the lower end of the set screw 98 below the lower surface of the lever 46, the relative position of the levers 70 and 46 at which the set screw 98 will engage the pin 95 may be varied. Eventually, as the levers are brought into closer relationship, the set screw 98 will cause the pin 95 to be pressed downwardly sufficiently to release the end 93 of the spring clip 91 from the serrations 94 in the shaft 82 to permit the shaft to be operated by the spring 86, causing the tooth 84 to lock between the teeth 75 of the rack 74.

After the steel strap has been positioned about the core loop, as shown in Fig. 1, and the end 7

extending through the clip 8 and bent at 9 under the main body of the strap 6 and the outer end 11 of the strap extending through the clip 8 between the bodies 32 and 33 of the tooth and gripped between the members 18 and 17, the tool is ready for operation to stretch the strap 6 about the core loop 2. The locking member 81 is then in the unlocked position as illustrated in Fig. 4 with the shaft 82 being held in the unlocked position by the end 93 of the spring clip 91. The hand of the operator is then grasped about the handle 43 and the lower portion of the secondary lever 70 and the fingers successively compressed to effect successive upward movement of the levers 70 and 46 to cause successive lowering and raising of the pawl 42 to operate the ratchet wheel 38 in a clockwise direction as viewed in Fig. 2, this motion being communicated through the pinion and the teeth 31 on the rack bar 28 to cause the head 29 of the tool to move toward the left as illustrated in the drawings, or away from the frame portion of the tool. The end 11 of the steel strap slides between the members 32 and 33, which members force the clip 8 toward the left, the end 11 of the strap being held by the members 17 and 18 as the strap is tightened about the core. The force applied to the lever 70 is conveyed to the lever 46 through the springs 78. As the strap tightens about the core, the force necessary for successive movements of the pawl 42 increases so that the force conveyed from the lever 70 to the lever 46 correspondingly increases. The lever 70 comes closer to the lever 46 and upon the transmission of a predetermined force between the two levers, the pin 95 is moved downwardly by the set screw 98, forcing the end 93 of the retaining spring from engagement with the shaft 82 permitting the shaft to be operated by the spring 86 toward the right, as viewed in Fig. 4, causing the tooth 84 to engage between teeth 75 of the rack 74 to lock the lever system against further movement of the pawl 42 and further tightening of the strap. In the locked position, the force communicated from the lever 70 through the lever 46 and the pawl 42 is continuously applied through the springs 78, thus preventing locking the lever system in a position where a much higher force than that desired is applied to the strap as is possible where the lever 46 is locked instead of the lever 70. This will be understood by comparing the diagrammatic showing of the two different applications of the locking means in the lever system as shown in Figs. 7 and 8.

Fig. 7 is a diagrammatic view of a lever system in which the lever 46 is locked, when a predetermined force is communicated from the lever 70 to the lever 46 through the spring members 78. In the system diagrammatically illustrated in Fig. 7, the locking device 81 is carried on the lever 46 and when released locks the lever 46 in a fixed position, thus applying a force to the pawl 42 dependent upon this position. Since the lever 46 may be required to move slightly due to the tooth 84 striking one of the teeth 75 after the force through the springs 78 has reached a value to release the locking mechanism, it is possible that the force on the strap has been unduly increased before this lever is finally locked, and this is particularly true in the case of very small core loops where the amount of stretch upon a single movement of the lever system of the tool stretching device is a relatively larger proportion of the length of the strap about the loop

than would be the case in a larger loop employing a longer strap. Fig. 8 diagrammatically illustrates the arrangement of the lever system and locking mechanism illustrated in Figs. 1 to 6, in which the locking mechanism is carried on the lever 70 and the force applied to the pawl 42 is communicated from the lever 70 through the springs 78 to the lever 46 after the lever 70 has been locked, so as to cushion or "weigh" the force thus applied, and thus prevent an undue increase in this force above the force between the two levers required to release the locking mechanism.

It will be seen that in the mechanism disclosed as illustrating an embodiment of my invention, if the locking pin 84 is tripped when the lever 70 carrying it is in a position such that it will engage the end of tooth 75 of the locking rack, so that it is necessary to move the lever 70 further to permit the pin 84 to engage between two adjacent teeth 75 on the rack, the springs 78 between the two levers 46 and 70 will absorb the additional movement of the lever 70 required for the locking pin to engage between the teeth 75 and no substantial increase in the force applied to the band will result.

It will be understood by those skilled in the art that modifications may be made in the details of the structure illustrated and described without departing from the spirit of my invention, and it is intended that the above description of a preferred embodiment of the invention be taken as illustrative of the invention and not in a limiting sense.

I claim as my invention:

1. The combination in a strap stretching device, of a pair of relatively movable members, means carried by each of said relatively movable members and constructed to grip the ends of a flat metal strap with said ends overlapping one above the other, and means for moving said relatively movable members away from each other for drawing the strap taut about an article and maintaining said overlapping portions in taut condition, a pair of levers mounted at their inner ends on the frame of the device and extending outwardly therefrom in the same general direction, a plurality of compressible members positioned between said two levers and spaced at intervals along the length thereof for transferring force applied to one of said levers to the other of said levers for operating the stretching device, and means operable upon the application of a predetermined force between said levers for locking the lever to which the force is first applied against further movement.

2. The combination in a strap stretching device of a frame, a rack bar having movement in said frame, means carried by said bar and said frame for engaging a strap, means carried by said frame including a ratchet wheel for effecting movement of said rack bar relative to said frame, a pawl adapted to engage said ratchet wheel, a handle mounted in fixed position on said frame, a lever pivotally mounted at its inner end on the frame of said device for operating said pawl, a second lever pivotally mounted adjacent the inner end of the first named lever and extending outwardly along the first named lever and adapted to be manually engaged and operated, a plurality of spring members positioned between said two levers and spaced at intervals along the lengths thereof for transferring force from the manually engaged second named lever to the first named lever for operating the stretching device,

and means operable upon the application of a predetermined force between said levers for locking said second named lever against further movement.

3. The combination in a strap stretching device, a pair of relatively movable members, means carried by each of said relatively movable members and constructed to grip the ends of a flat metal strap with said ends overlapping one above the other, and means for moving said relatively movable members away from each other for drawing said strap taut around an article and maintaining said overlapping portions in taut condition including a lever pivotally mounted at its inner end on the frame of the device, a lever pivotally mounted adjacent the inner end of the first named lever and extending outwardly along the first named lever, the second lever having side portions spaced to move along opposite sides of the first named lever and a body portion connecting the side portions, a plurality of recesses along the adjacent sides of the two levers and spring members having their opposite ends in the recesses in the two levers for biasing the two levers away from each other, and means operable upon the application of a predetermined force between the two levers for locking the lever to which the force is first applied against further movement for holding the device in locked position with a predetermined force on the strap that is applied continuously through the springs between the two levers after the one lever is locked.

4. The combination in a strap stretching device, a pair of relatively movable members, means carried by each of said relatively movable members and constructed to grip the ends of a flat metal strap with said ends overlapping one above the other, and means for moving said relatively movable members away from each other for drawing said strap taut around an article and maintaining said overlapping portions in taut condition including a lever pivotally mounted at its inner end on the frame of the device, a second lever pivotally mounted adjacent the inner end of the first named lever and extending outwardly along the first named lever and adapted to be manually engaged and operated having spring means between the two levers for biasing the two levers away from each other and for communicating force applied to the manually operated second named lever to the first named lever for operating the relatively movable members, and means operable upon the application of a predetermined force between the two levers for locking the lever to which the force is first applied against further movement for holding the device in locked position with a predetermined force on the strap that is applied continuously through the spring means between the two levers after the one lever is locked.

5. The combination in a strap stretching device, of a pair of relatively movable members, means carried by each of said relatively movable members and constructed to grip the ends of a flat metal strap with said ends overlapping one above the other, and means for moving said relatively movable members away from each other for drawing said strap taut around an article and maintaining said overlapping portions in taut condition comprising a lever pivotally mounted at its inner end on the frame of said device, a second lever pivotally mounted adjacent the inner end of the first named lever and extending outwardly along the first named lever

for operating the first named lever, spring means between the two levers for biasing the two levers away from each other and for communicating force applied to the second named lever to the first named lever, and means operable upon the application of a predetermined force between said levers for locking said second named lever against further movement, said means including a locking member slidably mounted on said second named lever and biased for movement outwardly from the pivotal support of the lever, a rack extending along the path of travel of the outer end of the lever and provided with teeth for receiving the locking member, a latch member normally retaining the locking member from engagement with the rack, and means for tripping the latch member upon a predetermined relative movement of the two levers upon compression of the biasing means between them for holding the device in locked position with a predetermined force on the strap that is applied continuously through the spring means between the two levers after the one lever is locked.

6. The combination in a strap stretching device, of a pair of relatively movable members, means carried by each of said relatively movable members and constructed to grip the ends of a flat metal strap with said ends overlapping one above the other, and means for moving said relatively movable members away from each other for drawing said strap taut around an article and maintaining said overlapping portions in taut condition including a pair of levers mounted at their inner ends on the frame of the device and extending outwardly therefrom in the same general direction, spring means positioned for transferring force between the two levers for operating the stretching device, and a single locking means operable upon the application of a predetermined force between said levers for locking one of said levers against further movement in either direction for holding a predetermined force on the strap that is applied continuously through the spring means between the two levers after the one lever is locked.

7. The combination in a strap-stretching device, of a frame, a rack bar having movement in said frame, means carried by said bar and said frame for engaging a strap, means carried by

5 said frame including a ratchet wheel for effecting movement of said rack bar relative to said frame, a pawl adapted to engage said ratchet wheel, a handle mounted in fixed position on said frame, a lever pivotally mounted on its inner end on the frame of said device for operating said pawl, a second named lever pivotally mounted adjacent the inner end of the first named lever and extending outwardly along the first named lever, a spring member positioned for transferring force from the second named lever to the first named lever for operating the stretching device, and a single locking means operable upon the application of a predetermined force between said levers for locking said second named lever against further movement in either direction for holding the device in locking position with a predetermined force on the strap that is applied continuously through the spring member between the two levers after the one lever is locked.

8. The combination in a strap-stretching device, of a pair of relatively movable members, means carried by each of said relatively movable members and constructed to grip the ends of a flat metal strap with said ends overlapping one above the other, and means for moving said relatively movable members away from each other for drawing said strap taut around an article and 10 maintaining said overlapping portions in taut condition including a lever pivotally mounted at its inner end on the frame of said device, a second lever pivotally mounted adjacent the inner end of the first named lever and extending outwardly along the first named lever for operating the first named lever, biasing means positioned for transferring force from the second named lever to the first named lever for operating the stretching device, and a single locking means operable upon the application of a predetermined force between said levers for locking said second named lever against further movement in either direction for holding the device in locked position with a predetermined force on the strap that is applied continuously through the biasing means 15 between the two levers after the one lever is locked.

FRED H. HOFING.
